UNITED STATES PATENT OFFICE.

RICHARD STRESAU, OF WAUWATOSA, WISCONSIN, ASSIGNOR TO A. O. SMITH CORPORATION, OF MILWAUKEE, WISCONSIN, A CORPORATION OF NEW YORK.

CENTRIFUGAL CASTING.

Application filed July 19, 1923. Serial No. 652,495.

To all whom it may concern:

Be it known that I, RICHARD STRESAU, a citizen of the United States, and a resident of the city of Wauwatosa, in the county of 5 Milwaukee and State of Wisconsin, have invented certain new and useful Improvements in Centrifugal Castings; and I do declare the following to be a clear, exact, and complete description thereof, such as will 10 enable others skilled in the art to which the invention pertains to use and practice the same.

My invention relates in general to the casting of tubular articles, and in particular 15 to pipe couplings, by the centrifugal process in which a measured quantity of molten metal is poured into a cylindrical mold during the rotation of the latter. By virtue of the rotation of the mold upon its longitudinal 20 axis at a high rate of speed, the metal is caused by centrifugal force to flow evenly against the molding surface so as to cover the same with a substantially uniform density, and produce a hollow casting, the 25 walls of which are of uniform thickness throughout.

Although this manner of casting is a simple matter and is easily accomplished, it is found that the casting in chilling sometimes 30 sticks to the steel mold, requiring an expenditure of time in removing the casting from the mold, as well as incurring an interruption of the casting operations due to such exigency.

My present invention comprises the provision of a means for remedying the adverse conditions referred to, and through 35 which I am enabled to practice centrifugal casting in a manner in which all liability of the casting to stick to the mold is eliminated, and to permit discharge of the casting from the mold without loss of time or interruption of the casting operation as a continuous one.

This result I achieve by inserting in the mold prior to each casting operation a lining formed as a thin sheet of metal having substantially the character and properties of the metal being cast. The lining sheet conforms closely to and completely covers the 50 curved molding surface, and may or may not be joined at its meeting edges.

The lining will be fused by the molten metal, as the latter is introduced into the mold during the rotation of the latter, and

be incorporated as an integral part of the casting. But the low temperature existing between the contiguous surfaces of the mold and the lining will act as a chill to overcome any tendency which the casting might have 60 to stick to the mold.

Although the lining is fused into the casting, the finished exterior of the rolled sheet from which the lining is formed is preserved practically in its primary state, so 65 that a much better finish is imparted to the outer surface of the casting, in that the surface cracks usually formed upon centrifugal castings are eliminated.

In the drawing which accompanies this 70 specification, I have shown conventionally a centrifugal casting machine, by means of which the invention may be reduced to practice. I will now proceed with a specific description of the machine shown, together 75 with a statement as to the operation of the same in carrying out my invention, and will conclude with claims defining the novelty of the latter.

In the drawings:

Figure 1 is a longitudinal sectional view through the vertical axis of a water-cooled centrifugal casting machine, built in accordance with my invention, and preparatory to the casting operation.

Fig. 2 is a vertical sectional view of the machine shown in Fig. 1, on a line transverse to the axis of the mold, and taken at any point between the ends of the mold.

Referring to the drawing, the numeral 10 indicates the cylindrical hard metal mold of a centrifugal casting machine designed for use in casting tubular articles. The mold is provided with heads 11 and 12 having journals 13 and 14, which are mounted for rotation in bearings 15 and 16. The journal 15 is provided with driven means, as a belt pulley 17, through which a movement of rapid rotation is imparted to the mold 10. The journal 16 is hollow and open from end to end, so that the molten metal may be introduced into the mold through the funnel or trough 18, the discharging end of which passes through the hollow journal and into the mold. The funnel or trough may be supported in relatively fixed position upon the bearing 16 by means of the bracket 19, or it may be independently supported with capacity for axial movement with relation to the mold. In the particulars 100 105 110

described, the arrangement is quite usual. It will increase the capacity for production by the apparatus to provide the mold with a concentrically arranged covering 20, spaced 5 from the mold to constitute a water jacket, so that water may circulate through the space 21 and effect reduction of the temperatures within the molds.

But in the absence of any provision of 10 cooling means, and even when used, it sometimes occurs that the casting will stick to the mold, and can be dislodged therefrom only by an expenditure of time and labor, with a consequent unnecessary interruption and 15 delay in casting as a continuous operation.

My invention obviates these difficulties 20 and delays. In achieving its purposes, I line the mold with a thin sheet of metal having the properties of the metal which is being cast. The lining occupies the length of 25 the mold and is in the form of a tube 22, either seamed or not at the meeting edges 23 of the sheet out of which it is formed, and bears a snug contact with the whole of 25 the inside surface of the mold.

When ready for casting the mold is lined 30 as described and rapid rotation imparted thereto. Molten metal in a measured quantity is introduced into the mold, and quickly 35 distributes itself evenly over the interior surface of the lining, due to centrifugal force, with the result that a casting uniform in the density and thickness of its tubular wall is produced. The contact of the molten 40 metal with the lining fuses the latter into such a state that it becomes an integral part of the casting, and loses its character as a shell in the amalgamation which takes place.

Although the fusion of the lining is 45 complete, the casting will not stick to the mold, due to the lower temperature created by the contact of the surfaces of the hard metal mold and the lining, whereby a chilling effect is produced in the area of such contact. 50 The proportions of the casting are indicated by the broken lines in the drawing.

The practice of my invention has enabled 55 me to produce a better finish upon the outer surface of the casting, inasmuch as the original surface of the rolled sheet from which

the lining is shaped is preserved in much of its entirety, and the surface cracks usually formed upon centrifugal castings are obviated.

Although my invention is specifically applicable to the centrifugal casting of pipe couplings, it obviously is not so limited, but may be applied to the production of other articles.

The pipe coupling per se forms the subject-matter of the claims of a divisional application Serial No. 18,229, filed by me on March 25, 1925.

Having thus described my invention, what I claim and desire to secure by Letters Patent of the United States, is:

1. The process of casting a pipe coupling which comprises the steps of lining a mold with a thin sheet of metal, introducing into the mold during the periods of rotation of 70 the latter a quantity of molten metal, and fusing and amalgamating the lining into a finished integral exterior surface of the tubular casting free from cracks.

2. The process of casting a pipe coupling 75 which comprises the steps of lining a rotatable mold with a thin sheet of metal, introducing into the rotating mold a quantity of molten metal in the form of a layer of uniform thickness, and fusing and amalgamating the lining as an integral part of the casting by the centrifugal contact of the molten metal therewith, to constitute a finished exterior surface for the casting free from 80 cracks.

3. In centrifugally casting pipe couplings, the method of preventing the casting from sticking to the mold, which consists in lining a metal mold with sheet metal prior to the introduction of molten metal into the mold, 90 to form a chill between the surface of the mold and the molten metal, and fusing the lining in the contact of the molten metal therewith so as to constitute an integral exterior surface for the casting free from 95 cracks.

In testimony whereof, I have signed my name at Milwaukee, this 17th day of July, 1923.

R. STRESAU.
